RAOUL PRUGER, OF PITTSBURGH, AND JOHN L. BROWN, OF WILKINSBURG, PENNSYLVANIA, ASSIGNORS TO WESTINGHOUSE ELECTRIC AND MANUFACTURING COMPANY, A CORPORATION OF PENNSYLVANIA.

OIL-OVERFLOW PLUG.

Application filed March 1, 1923. Serial No. 622,094.

To all whom it may concern:

Be it known that we, RAOUL PRUGER, a citizen of the United States, and a resident of Pittsburgh, in the county of Allegheny and State of Pennsylvania, and JOHN L. BROWN, a citizen of the United States, and a resident of Wilkinsburg, in the county of Allegheny and State of Pennsylvania, have invented a new and useful Improvement in 10 Oil-Overflow Plugs, of which the following is a specification.

Our invention relates to oil overflow plugs and it has particular relation to plugs having their overflow portions provided 15 with covers.

Considerable difficulty has been experienced with covered overflow plugs, when employed to drain excess oil from bearings, because of the siphoning of the oil from the 20 bearing, by reason of a partial-vacuum condition being established at the covered overflow portion thereof. When such condition has occurred, the oil would continue to drip from the edge of the overflow, where an oil 25 seal had formed between the edge of the overflow portion of the plug and its cover, until such time as the oil head was lowered sufficiently to resist the capillary action, thus breaking the seal.

The problem of preventing siphoning, while protecting the overflow plug from dirt, is an exceedingly difficult one, owing to the fact that oil films will form persistently over even large-sized openings, thus 30 hermetically sealing the cap-portion of the plug. It was only after much experimenting and redesigning of the covered overflow plug that a successful cure for the siphoning evil was devised by the combination of 35 a number of improved features operating in conjunction.

The object of our invention is, therefore, to provide an overflow plug structure, wherein the siphoning of the oil from the 40 bearing is entirely eliminated.

In the accompanying drawing:

Figure 1 is a plan view of our improved overflowing plug,

Fig. 2 is a view in longitudinal section 50 thereof, on the line II--II of Fig. 1, and

Fig. 3 is a view in cross section thereof, on the line III--III of Fig. 1.

As shown in the drawing, the device comprises a substantially bowl-shaped overflow

body portion 1, provided with an integral 55 stem-like extension 2, having its end threaded for connection with a bearing, (not shown). The bowl portion is further provided with a suitable abutment lug 3 and, at a point opposite thereto, with a hinge 60 lug 4. A cover 5, preferably of dome shape, with a dependent flange portion 6, and of substantially like but greater contour than the overflow body, is provided. The flange portion of the cover is extended a short distance at its rear to provide hinge lugs 7 by which it is connected to the hinge lug 4 of the overflow body, by a hinge pintle 8. The forward end of the cover flange 6 rests upon the abutment lug 3 of the overflow bowl. 70 When the lid is thus disposed, an overflow space is provided all the way around the bowl and over the edge thereof, as shown.

In practice, when an excessive amount of oil is supplied to a bearing, the housing of 75 which is equipped with my device, the oil rises in the bowl 1, and as there is sufficient space about and above the edge thereof and lid, the excess oil is free to drip from the edge of the bowl. The space just mentioned 80 is not only sufficient to permit the excess oil to pass freely over the bowl edge, but an air space is left between the bowl edge and the lid, whereby the possibility of any siphoning of the oil from the bearing, as a result 85 of an oil seal formed between the bowl and, lid is eliminated.

It has been found desirable to provide a cover of hollow form, leaving considerable 90 air space above the oil surface, in addition to the air and overflow space between the cover and bowl. In case the housing should be filled too rapidly, so that the oil-head rises faster than the overflowing operation 95 can compensate therefor, the hollow space in the cover may become filled with oil, tending to produce a siphoning effect. An air hole 9 has, therefore, been provided in order to prevent the occurrence of a vacuum condition.

By extending the cover down below the edge of the overflow bowl, the entrance of foreign matter is prevented.

While we have shown and described a certain embodiment of our invention, it will 105 be evident that modifications may be adopted within the spirit of our invention. We desire, therefore, that the appended claims

shall be accorded the broadest construction, consistent with the prior art.

We claim as our invention:

1. An oil overflow device comprising a hollow plug having an elevated overflow body portion and an overhanging cover supported above the overflow portion to provide free overflow space therebetween.
2. On oil overflow device comprising a hollow plug having an elevated overflow body portion and a cover hingedly secured thereto, said cover being of hollow structure and extending over and below the edge of said body portion and leaving an interiorly communicating overflow space thereabout.
3. An oil overflow device, comprising a hollow plug having an elevated overflow body portion and a cover hingedly secured thereto, and provided with an air orifice, said cover being of hollow structure and extending over and below the edge of said body portion and leaving an interiorly communicating overflow space thereabout.
4. An oil overflow device comprising a hollow plug having an elevated and enlarged overflow body portion at its free end and having a cover abutment, and a substantially dome shaped cover hinged to said body portion and having its free end engag-

ing said abutment, said cover extending below the edge of the overflow body and providing free overflow space.

5. An oil overflow device comprising a hollow plug having an elevated and enlarged overflow body portion at its free end and having a cover abutment, and a substantially dome shaped cover provided with an air orifice and hinged to said body portion, said cover having its free end engaging the abutment thereof, and extending below the edge of the overflow body and providing free overflow space.

6. An oil overflow device comprising a hollow plug having an elevated and enlarged overflow body portion provided at its free end with a cover abutment, and a cover hinged to said body portion and engaging said abutment, said cover extending below the edge of the overflow body to provide free overflow space and having its central portion elevated to provide a greater air space thereat than at the edge of the overflow.

In testimony whereof, we have hereunto subscribed our names this 21st day of February, 1923.

RAOUL PRUGER.
JOHN L. BROWN.
